UNITED STATES PATENT OFFICE.

SAMUEL N. BURNS, OF HARGROVE, ALABAMA.

RAIL-JOINT LOCK.

1,242,764.

Specification of Letters Patent.

Patented Oct. 9, 1917.

Application filed March 2, 1917. Serial No. 152,077.

To all whom it may concern:

Be it known that I, SAMUEL N. BURNS, a citizen of the United States, residing at Hargrove, in the county of Bibb and State of Alabama, have invented new and useful Improvements in Rail-Joint Locks, of which the following is a specification.

This invention relates to rail joints, and the objects of the same are to provide a comparatively simple device of the class specified wherein the use of rail connecting bolts is avoided; to insure a tight joint relatively to the abutting ends of rails and of such arrangement as to allow the rails to expand and contract without dangerously affecting the joint and also to guard against lateral displacement of the rails, and to so associate the members or parts of the joint locking means as to render them readily applicable to rails and separable from the latter, and, further, to prevent the depression of the rails at their abutting ends with material advantages in avoiding wear on the rail ends and also causing an easier riding action of the rolling stock over the rail joints.

With these and other objects and advantages in view the invention consists in the construction and arrangement of the several parts which will be more fully herein-after described and claimed.

In the drawing:

Figure 1 is a perspective view of portions of rails illustrated in joint relation and showing the improved means for locking the joint.

Fig. 2 is a transverse vertical section through the rails and locking joint means taken in the plane intersecting opposite fastening devices engaging parts of the joint means.

Figs. 3 and 4 are detail perspective views of parts of the locking means.

The numerals 5 and 6 designate rails which are abutted endwise to form a joint in the usual manner, each rail being provided with a vertical web 7 and a base flange 8 of well known form. The improved locking means comprises a chair 9 embodying a horizontal base 10 and upstanding side flanges 11, the inner surfaces of the flanges 11 being far enough apart to permit the base flanges 8 of the rails to be readily inserted between the same and rest firmly on the base plate 10 of the chair. The base 10

of the chair is extended at each end and formed with openings or slots 10^a to receive spikes, shown in dotted lines in Fig. 1, to hold the chair in applied position, said spikes also engaging the rail flanges. The inner surfaces of the flanges 11 are perpendicularly straight, as shown by Fig. 2, and the opposite side edges of the base flanges 8 of the rails have a close fitting relatively to the lower portions of said inner surfaces 65 of the side flanges. The remaining members or parts of the locking means consist of two splice bars 12, two wedge bars 13, and fastening devices 14. Each bar 12 has an upwardly inclined flange 15 extending from an intermediate angular bend 16, the upper end of the flange 15 being laterally extended as at 17 and having an inwardly beveled top surface 18 to closely fit under and positively engage the under side of the head or ball 19 75 of each rail 5 and 6. From the angular bend 16 the splice bar is formed with a depending foot or support flange or member 20 having an outer inclined face 21 and a lower foot 22 with a lower surface 23 to bear on 80 the rail flanges 8 close to the outer side edges of the latter, as shown by Fig. 2. The side flanges 11 of the chair 9 have horizontal slots 24 formed therein near each end, these slots being upwardly inclined and adapted 85 to coöperate with slots 25 opening outwardly through the opposite ends of the foot or supporting flanges 21 of the bars 12. The wedge bar 13 is formed in duplicate and is of the same length as the side flanges 11 90 of the chair 9, each wedge strip having an upwardly inclined slot 26 formed therethrough adjacent to each end of the same. These slots are for receiving fastening devices in a manner which will be more fully 95 hereinafter explained.

In assembling the parts or members of the improved locking means the abutting ends of the rails 5 and 6 are first seated in the chair 10 and held in longitudinal alignment and prevented from the least lateral shifting movement in view of the contiguity of the opposite side edges of the base flanges 8 of the rails to the inner perpendicular surfaces of the side flanges 11. In 105 view of the fact that the base flanges 8 of the rails bear on the base plate or member 10 of the chair, depression of the rail ends is obviated. After the rails have been seated in the chair as just explained the 110

bars 12 are inserted between the under portions of the opposite sides of the head 19 and the base flange of each rail and extend equally across the joint, the two bars when 5 properly applied being positioned as shown by Figs. 1 and 2. The wedge bars 13 are then inserted between the outer inclined surfaces of the flanges 22 of the bars and the perpendicular inner surfaces of the side 10 flanges 11 of the chair, the wedge bars being firmly driven downwardly and having their inclined faces bearing against the outer inclined surfaces 21 of the flanges 22. As the wedge bars 13 are driven downwardly in place they force the bars inwardly 15 toward each other and establish a positive and firm engagement of the upper and lower edges of the bars with the rail heads 19 and base flanges 8 of the rails. When the wedge 20 bars 13 are driven downwardly they are secured by fastenings 27 inserted through the slots 24, 26 and 25 respectively formed in the flanges 22 of the bars, the wedge bars 13, and the opposite ends of the chair, and 25 by means of these fastenings, which may be of any preferred form, all the parts of the locking means are reliably held in coordinated relation and movement of the wedge bars away from a maximum wedging 30 engagement with relation to the side flanges 11 of the chair 9 and the foot or supporting flanges 21 of the bars 12 is prevented, and the fastening devices 27 will be held against loose movement by a binding 35 action set up between the walls of the slots which they engage and the said fastening devices at different points along the length of the latter. As above noted, any form of fastening device of a readily removable character may be used to connect the several parts of the locking means, but it has been found by experiment that the split key form of locking device as shown 40 serves as a very convenient means for securing the several parts of the locking means against displacement, the said split keys having their ends 28 spread apart and upset against the inner side portions of the bars 12, as shown by Fig. 2, and thereby 45 obstruct the disengagement of the keys or locking devices from their applied positions. The ends of the keys may be very easily reached at opposite ends of the chair and in view of the spaces 29 formed between 50 the inner sides of the bars 12 and the webs 55 7 of the rails.

The parts of the locking means may be readily applied over the abutting ends of the rails and secured to effectively hold the 60 rail ends against vertical movement and particularly against depression and lateral displacement. The parts of the locking means, however, engage the abutted rail ends in such manner as to compensate for 65 expansion and contraction, and also prevent

lateral displacement of the rails, the rail ends always being held for accurate alignment and the weight pressure on the rail heads is in part taken up by the bars 12 and by the latter directly imposed on the 70 base flanges of the rails, and under these conditions the bars serve as auxiliary weight sustaining means and have a tendency to solidify the joint between the rail ends. At any time the parts of the locking means 75 may be dissociated or separated from each other and the rails by withdrawing the fastening devices 27 and removing the wedge bars 13. At any time desired the bars 12 may be tightened should they work loose 80 in view of wear thereon by driving the wedge bars downwardly a greater distance and resetting or reapplying the fastening devices 27. One of the main structural advantages of the improved locking means is 85 that the bars and wedge bars are of duplicate construction and may be readily manufactured in large quantities at a materially reduced cost, and if it ever becomes necessary to replace either of said parts the part 90 requiring replacement may be readily supplied. The chair 9 is also of simple construction and may be readily manufactured in any approved manner.

What is claimed as new is:

1. In a rail joint lock, the combination with abutting rail ends, of a chair in which the abutting extremities and base flanges of the rails are disposed, the chair having side flanges with inner perpendicular surfaces, 95 angularly formed splice bars engaging the opposite side portions of the rail heads and the base flanges of the rails, wedge bars inserted between the outer sides of the lower portions of the splice bars and the side flanges of the chair and extending full length of said flanges, and fastening devices removably inserted through the side flanges of the chair, the wedge bars and the opposite ends of the splice bars.

2. In a rail joint lock, the combination with rails having abutting ends and base flanges, of a chair in which the base flanges of the rails are inserted, the chair being formed with opposite side flanges, splice 100 bars inserted between the opposite sides of the rails over the joint and the side flanges of the chair, the splice bars being each of angular form and having an upper head to bear closely against the under side of the rail 105 heads and a lower foot flange to bear on the base flanges of the rails adjacent to the side edges of the latter, continuous wedge strips or bars inserted between the side flanges of the chair and the foot flanges of the splice 115 bars and operating to force the latter bars inwardly in tight engagement with the rails, the side flanges of the chair, the wedge bars and the splice bars having slots in their opposite extremities which are adapted to reg- 120 125 130

ister, and split keys removably inserted in the slots of the chair flanges, the wedge bars and the splice bars.

3. In a rail joint lock, the combination with abutting rail ends, of a chair in which the abutting ends and base flanges of the rails are disposed, the chair having side flanges extending upwardly therefrom, angularly formed splice bars engaging the opposite side portions of the rail heads and the base flanges of the rails, wedge bars inserted between the outer sides of the lower portions of the splice bars and the side flanges of the

chair and extending full length of said flanges and splice bars, and fastening devices removably inserted through the flanges of the chair, the wedge bars and the opposite ends of the splice bars. 15

In testimony whereof I have hereunto set my hand in presence of two subscribing witnesses. 20
